UNITED STATES PATENT OFFICE.

JOHN F. WENTWORTH, OF ROCHESTER, NEW HAMPSHIRE.

INTERNAL-COMBUSTION ENGINE.

1,205,584.

Specification of Letters Patent. Patented Nov. 21, 1916.

Application filed May 13, 1910. Serial No. 561,195.

To all whom it may concern:

Be it known that I, JOHN F. WENTWORTH, a citizen of the United States, residing at Rochester, in the county of Strafford and 5 State of New Hampshire, have invented a certain new and useful Internal-Combustion Engine, of which the following is a specification.

My invention relates to internal combustion engines designed to work under the conditions of a steam engine, and it has for its 10 object to provide an engine with an efficiency greater than that of the best type of internal combustion engine with which I am 15 familiar is capable.

The principal idea involved in my invention is to store the energy needed to start, reverse, or to maneuver, in a body of hot water, instead of compressed air, and this 20 I accomplish by the means and mechanism hereinafter described and claimed.

In the accompanying drawings forming a part of this specification, Figure 1 is a plan view of my improved engine. Fig. 2 is 25 a side elevation, partly in section, of the same. Fig. 3 is a detail vertical section through the starting valve. Fig. 4 is a longitudinal vertical section through the engine. Fig. 5 is a detail horizontal section 30 on the line 5—5, Fig. 4. Fig. 6 is a detail horizontal section on the line 6—6, Fig. 4. Fig. 7 is a detail vertical section on the line 7—7, Fig. 6.

Similar letters refer to similar parts 35 throughout all the views.

The present type of heavy oil engines requires compressed air as a starting medium, and the standard engines start and reverse by the use of compressed air, but its use is 40 objectionable and inconvenient by reason of its bulk when stored in quantities to supply any great amount of power, and by reason of the fact that a small leak will cause the engine to become "dead" until a new supply 45 of air is furnished, from some outside source.

My invention is designed primarily to provide an element as a substitute for compressed air in starting, reversing, and maneuvering an engine which may be produced quickly and supplied in constant quantities without adding inconveniently to the size of the plant, and without the employment of a cumbersome and bulky tank such as is required to store compressed air.

55 Referring to the drawings the numeral 1

represents the cylinder, 2 the cylinder head, 3 the exhaust valve, 4 the admission valve, 5 the starting valve, and 6 the fuel valve, all of which may be of the usual or any preferred type or form.

A pump 7 is provided for causing a circulation of the cooling water from a tank 8 to and through the cylinder jacket through the medium of the supply pipe 9 connecting the tank and the pump 7, and the pipe 10 connecting the pump and the water jacket, and the discharge pipe 11 leading from the water jacket to the tank, a suitable valve 12 being provided for the supply pipe to regulate the supply to the water jacket of the 70 cylinder.

A fuel pump 13 is provided from which leads the pipe 14 to the fuel valve 6, and also a feed pump 15 from which the pipe 16 leads to the steam generators, said pipe 16 75 being provided with a valve 16^a and a branch pipe 17, leading to and connecting with a return pipe 39 and having communication through said pipe with an auxiliary boiler 18, and said pipe 17 being provided with a valve 19 to control the flow therethrough, and with a branch 20, having a valve 21, which connects with the steam pipe 22 from said boiler, and a branch 23 leading to and forming a coil 24 in the combined muffler 80 steam accumulator, and air inlet heater 25. The auxiliary boiler is or may be of any standard type of steam generator, and the heat may be applied thereto in any preferred manner. The pipe 22 is provided with a 90 regulating valve 22^a to control the flow through said pipe. The coil 24 is located in the neck of the muffler, at which point the exhaust gases entering the muffler are hottest, whereby the water from the pump 15 95 may be converted into steam at high pressure before delivery to the fuel valve 6 through the pipe 28 which forms a continuation of the coil 24. The muffler 25 is composed of an outer shell 29 and an inner shell 100 30, the latter having a header 31 at each end, and the fire tubes 32 extending therethrough for the passage of the exhaust gases or products of combustion from the engine and in so doing heat the water surrounding said tubes in the inner shell. The muffler is also provided with a steam dome 33 to collect the steam generated in the inner shell 105 and deliver the same to the starting valve 5 through the pipe 34 and connected pipe 110

35 which leads to said starting valve, a globe valve 36 being provided to control the passage of steam, and a safety valve 37 being also connected with said pipes.

5 The water surrounding the fire tubes 32 is first heated from the steam coils 38 arranged centrally of the inner shell and receiving steam from the boiler 18 through the pipe 22, the water of condensation 70 10 caping back to the boiler by the return pipe 39, both pipes 22 and 39 being provided with suitable valves, 22^a and 41, respectively, whereby the steam from the boiler may be cut off if desired after the engine has started 15 and the temperature of the water in the muffler kept up by the heat from the exhaust gases passing through the fire tubes.

The air is delivered to the cylinder through the outer shell 29 and is heated first 20 by radiation from the inner shell over which it passes and then by the heat from the exhaust gases as it passes through the neck 42 to the pipe 43 on its way to the admission valve 4. The exhaust pipe 44 from the engine 25 extends through the neck 42 and is expanded to surround the coil 24, and the steam thereby generated in said coil is used to force the fuel into the cylinder.

In Figs. 6 and 7 is shown in detail the 30 arrangement of the fuel valve and in which 14 is the pipe from the fuel pump, 28 the steam pipe, 45 the controlling valve seat, 46 the stem of the needle valve, 48 a shoulder or collar on the stem of the valve, 49 a coiled 35 spring surrounding the valve stem to cause the valve to return to its seat, 50 the bell crank lever engaging the collar 48 to unseat the valve, 51 the rod connecting the arm of the bell crank lever with the valve cams to 40 operate the valve, 52 an obstructed or tortuous passage formed in the oil receiving chamber and designed to prevent the fuel from being blown into the cylinder in a solid slug, 53 packing to prevent leakage of 45 steam, and 54 the pivot for the bell crank lever. The starting and controlling lever 69 is pivoted on a stub shaft 70 secured to the frame. This lever, 69, changes the operation of the engine by sliding the cam sleeve along 50 the cam shaft 61 to present a different set of cams 62 to the rollers at the ends of the four tappet rods. The piston 71 is connected to the wrist pin 55 of the connecting rod 56 mounted on the crank shaft 57, which carries 55 the fly wheels 58. A pinion wheel 59 on the shaft 57 meshes with a larger gear wheel 60 mounted on the cam shaft 61 on which are secured the cams 62, the latter being of the ordinary type used on internal combustion 60 engines. The rods 63 and 64 connected to cross heads or rockers 65 and 66, respectively, and having their lower ends engaging the valve cams operate the admission valve 4, and the exhaust valve 3, respectively, through their stems 67 and 68, re-

spectively, while the starting valve 5 is operated by the lever 73 through the rod 72 which is in engagement with the proper cam 62, in the usual manner.

In operation steam is generated in boiler 70 18 and passes through the pipe 22 to the steam coils 38 arranged in the inner shell 30 and thereby raising the temperature of the water in said shell 30 above the boiling point. From the shell 30 the steam is admitted 75 to the starting valve 5 through the pipe 35. The steam thus admitted acts similar to compressed air and starts the engine; fuel is admitted through the pipe 14 to the valve 6 and steam is admitted to the same 80 valve through the pipe 28 leading from the coil 24, and heated air is fed through pipe 43 to the valve 4. Steam to inject the fuel may be delivered from the boiler 18 through the pipes 22, 20 and 23 through the coil 24 85 and through pipe 28 to the fuel valve when the boiler is fed through the pipes 16 and 17 from the feed pump and valve 16^a is closed.

In starting a single cylinder engine of 90 this type the proper starting cams must be moved to engage the roller at the end of rod 72, this being done by means of the lever 69 and its connecting links, and the engine is 95 then given a part of a revolution till steam is admitted to the cylinder by the starting valve 5. In multiple cylinder engines inspection will show which piston is nearest the top of the cylinder on the down stroke and the engine can be started by lifting the 100 starting valve by hand. Or steam by-passes may be provided to each cylinder and the engine may be started by opening the throttle valve on the by-pass leading to the 105 proper cylinder.

Having thus described my invention, what I claim is—

1. The combination with an internal combustion engine, comprising starting and fuel valves, of a reservoir provided with 110 heating surface for heating water to a temperature corresponding with a fair working steam pressure, a pipe leading from the space above the water line in said reservoir to the starting valve, whereby the said engine may be started and reversed by the saturated steam generated by a reduction in pressure in said reservoir, and a high pressure steam boiler connected with the fuel valve of said engine, whereby the fuel may be driven into the engine against a high pressure of compression by means of the steam pressure behind the fuel in the fuel valve, means for first heating the water in the reservoir from the high pressure boiler, and means for maintaining the temperature thereof from the heat of the exhaust gases from the engine.

2. The combination, with an internal combustion engine having conventional admis- 130

sion exhaust and starting valves, of means for starting and maneuvering said engine, said means consisting of a primary steam generator and a secondary steam generator 5 in which water is heated from the energy generated in the primary generator, and a pipe connecting the steam space of the secondary generator with the starting valve, whereby the energy for starting said engine

may be derived from the energy stored in 10 the hot water in said secondary generator.

In testimony whereof, I affix my signature, in the presence of two witnesses.

JOHN F. WENTWORTH.
